DESIGN FOR A CRACKER

Rocco Forte, Madison, N. J.

Application December 5, 1944, Serial No. 116,709

Term of patent 3½ years

(Cl. D8—1)

To all whom it may concern:

Be it known that I, Rocco Forte, a citizen of the United States, residing at Madison, in the county of Morris and State of New Jersey, has invented a new, original, and ornamental Design for a Cracker, of which the following is the specification, reference being had to the accompanying drawing, forming a part thereof.

Fig. 1 is a plan view of one side of the cracker showing my new design.

Fig. 2 is a plan view of the other side of the cracker.

The cracker is of conventional thickness.

I claim:

The ornamental design for a cracker, as shown and described.

ROCCO FORTE.
